CHRISTMAS TREE ORNAMENT OR SIMILAR ARTICLE

Jack Burnbaum, 451 D St., Newton, Mass. 02110

Filed Oct. 24, 1966, Ser. No. 4,413

Term of patent 14 years

(Cl. D29—1)

Fig. 1.

Fig. 2.

Fig. 3.

FIG. 1 is a top plan view of a Christmas tree ornament showing my new design;

FIG. 2 is a front elevational view thereof, the back being plain, unornamented and opaque; and

FIG. 3 is a sectional view taken on the line 3—3 of FIG. 2.

I claim:

The ornamental design for a Christmas tree ornament or similar article, substantially as shown and described.
